ATTORNEY.

UNITED STATES PATENT OFFICE.

LOUIS DEL TURCO, OF NEWARK, NEW JERSEY.

DIVIDER FOR CEMENTITIOUS FLOORS.

1,401,590.

Specification of Letters Patent. Patented Dec. 27, 1921.

Application filed May 17, 1921. Serial No. 470,235.

To all whom it may concern:

Be it known that I, LOUIS DEL TURCO, a citizen of the United States, and a resident of Newark, county of Essex, and State of New Jersey, have invented certain new and useful Improvements in Dividers for Cementitious Floors, of which the following is a specification.

This invention relates to a divider used 10 in the laying of terrazzo and similar floors and is inserted in the underbed of the floor and projects up so as to be flush with the top surface or wearing surface of the floor, and not only localizes cracks if they appear, 15 but makes the laying of the floor less expensive as it saves time and labor.

The invention is designed to provide a strip which is easily made and easily installed in the work being done, and is constructed so that the strip keeps its position 20 in the floor even should cracks appear along the edge, and also in case there is a slight settling or buckling of the floor, since the strip is tightly secured against movement 25 up or down after it is in the floor.

The present strip is used similarly to the one described in my Patent No. 1,368,374, issued Feb. 15, 1921, and is adapted for use in the method described in said patent.

30 The invention is illustrated in the accompanying drawing, in which Figure 1 is a sectional perspective showing a form of my new strip in a floor, and Fig. 2 is a similar view of a modified form of strip.

35 The concrete foundation of the floor is shown at 10, and on this is laid the underbed 11, usually of cement, sand and grit, and while this is still wet the strip 12 is forced down through it, this being possible on account of the thin form of strip which is devoid of flanges or other obstruction. These strips can be either laid so as to form designs in the floor and at the same time subdivide the floor into panels or borders and

40 also localize any cracking that may take place, or are also well adapted for use in plain floors to form joints over beams, girders or other places where the floor is likely to crack. The strip is corrugated, usually to 45 form an ogee curve or an S-shaped curve 13 connecting upper and lower straight reaches 14 and 15, respectively, of the strip.

50 This curve offers no resistance to the insertion of the strip and the wet underbed 55 11 closes in around the strip and the curves thereof. After the underbed is set and hard,

the wearing surface 16 of terrazzo or similar material is laid, the strip being so firmly held that it maintains its position and the material of the layer 16 can be poured and troweled and rolled without displacing the strips, which, in their placing, were so disposed that their top edges are level with the finished floor.

When any cracking occurs it takes place 60 alongside the edge of the divider strip, where it is practically unnoticed. In case of cracking at this place the divider strip does not sink below the top surface of the floor, nor does it project therefrom in case of any 65 slight unevenness or settling of the floor due to such cracking, since the strip can not move relative to the floor either upward or downward, as the corrugated part holds it in position relative to the floor. Furthermore, this corrugation stiffens the strip so 70 that it maintains its straight formation when it is used preliminary to, or during, its insertion in the wet underbed of the floor.

75 In Fig. 2 I show a modified form of strip which includes a base 17 which is usually made of wood or some similar material that is expandable slightly when wet, which has the metal strip 12 inserted in its top edge 80 so that they are secured together and can be handled as a unitary article, the strip being corrugated, as at 18, adjacent to its connection with the base strip 17.

85 This form is preferably used where a sand cushion 19 is laid over the foundation 10, and then the underbed 11 is placed on the sand cushion and, in turn, is surmounted by the wearing or terrazzo surface 16. This structure is also held against any vertical 90 movement relative to the floor by reason of the corrugation being embedded in the floor, and the wooden base strip 17, when it is inserted in the wet underbed, swells on account of becoming wet, and when the underbed sets and becomes solid, the wooden base strip 17 dries out and performs the function 95 of an expansion joint, because when it dries it shrinks and leaves a void around the strip, that is, a clear space, since the wood 100 draws away from the underbed and leaves this space for expansion and for certain adjustments due to settlements and vibrations, and also has a tendency to localize at this 105 point any cracking that may occur in the floor, so that haphazard cracks or uneven cracks running over the panels of plain sur-

face of a floor are avoided, since these cracks are straight and alongside the strip and therefore unnoticed.

To make it easier to insert the strip shown in Fig. 2, and to force it down through the underbed 11, I provide said base strip with a pointed bottom edge, as shown at 20.

I claim:

1. A divider for use in terrazzo and similar flooring consisting of a strip of metal having a straight portion at its top edge and being corrugated intermediate of its top and bottom edges.

2. A divider for use in terrazzo and similar flooring consisting of an imperforate strip of metal having straight top and bottom edges and having a longitudinally extending corrugation between said edges.

3. A divider for use in terrazzo and similar flooring comprising a base strip of material adapted to be expanded when wet and

to shrink when dry, and a metal strip having straight top and bottom edges and a longitudinally extending corrugation between said edges, the bottom edge being secured to 25 said base strip.

4. A divider for use in terrazzo and similar flooring comprising a base strip of material adapted to be expanded when wet and to shrink when dry, said strip having its 30 bottom edge pointed, a metal strip having straight top and bottom edges and having a longitudinally extending corrugation intermediate of said edges, the lower edge of said metal strip being embedded in the top 35 edge of the base strip, whereby the two strips form a unitary article.

In testimony that I claim the foregoing, I have hereto set my hand, this 14th day of May, 1921.

LOUIS DEL TURCO.
